DESIGN FOR A GAME BOARD

Fred O. Paige, Philadelphia, Pa.

Application August 12, 1943, Serial No. 110,898

Term of patent 7 years

(Cl. D34—5)

To all whom it may concern:

Be it known that I, Fred O. Paige, a citizen of the United States, residing at Philadelphia, in the county of Philadelphia and State of Pennsylvania, have invented a new, original, and ornamental Design for a Game Board, of which the following is a specification, reference being made to the accompanying drawing, forming part thereof.

The figure is a top plan view of a game board showing my new design, the article being of conventional thickness.

I claim:

The ornamental design for a game board, substantially as shown and described.

FRED O. PAIGE.
